CLAIM

The ornamental design for a side glass, as shown and described.

DESCRIPTION

FIG. 1 illustrates a perspective view of a side glass in an open position according to the present disclosure;

FIG. 2 illustrates a right elevation view of the side glass of FIG. 1;

FIG. 3 illustrates a left elevation view of the side glass of FIG. 1;

FIG. 4 illustrates a front elevation view of the side glass of FIG. 1;

FIG. 5 illustrates a rear elevation view of the side glass of FIG. 1;

FIG. 6 illustrates a top plan view of the side glass of FIG. 1;

FIG. 7 illustrates a bottom plan view of the side glass of FIG. 1;

FIG. 8 illustrates a perspective view of the side glass of FIG. 1 in a closed position;

FIG. 9 illustrates a right elevation view of the side glass of FIG. 8; and,

FIG. 10 illustrates a left elevation view of the side glass of FIG. 8.

The broken lines in the drawings illustrate portions of the side glass which form no part of the claimed design.
